United States Patent Office.

HENRY E. DOSTER, OF BETHLEHEM, PENNSYLVANIA.

Letters Patent No. 81,610, dated September 1, 1868.

IMPROVEMENT IN CIGAR-PIPES.

The Schedule referred to in these Letters Patent and making part of the same.

TO ALL WHOM IT MAY CONCERN:

Be it known that I, HENRY E. DOSTER, of Bethlehem, in the county of Northampton, and State of Pennsylvania, have invented a new and useful Improvement in Cigar-Pipe; and I do hereby declare that the following is a full, clear, and exact description thereof, which will enable those skilled in the art to make and use the same, reference being had to the accompanying drawings, forming part of this specification.

This invention relates to an improved method of smoking tobacco, whereby all the advantages of a fine cigar may be enjoyed, without incurring the expense, and whereby the objections to the vulgar pipe are obviated.

And the invention consists in forming a smoking-pipe in the form of a cigar, and so as to resemble it in appearance in all respects.

It is made hollow, so that it may be filled with tobacco, and burned or smoked therein, like an ordinary cigar, as I will proceed to describe. The drawing—

Figure 1, represents a cigar-pipe constructed according to my invention.

Figure 2 is a longitudinal section of fig. 1, through the line *x x*.

Figure 3 is a cross-section of fig. 1, through the line *y y*.

Similar letters of reference indicate corresponding parts.

This cigar-pipe is formed of an inner metallic tube, *a*, seen in the sectional figures in yellow color.

A wooden or other tube, *B*, which covers the tube *a*, and then an outside covering or wrapper of paper, *c*, or other suitable material, which in color and appearance shall resemble tobacco, or the wrapper of a cigar.

D is the perforated mouth-piece, of wood, amber, or other material, which enters the wooden tube *B*, and strikes the end of the metallic tube *a*; as seen in the drawing.

E is a perforated piece of porcelain or other suitable material, which is inserted in the other end of the pipe.

This piece *E* is colored to resemble the ashes of a burning cigar, as seen in fig. 1.

Through the body of the cigar-pipe there are small perforations, as seen at *e*, which extend entirely through the shell or tubes, for the purpose of admitting air to the tobacco within.

F is the space within the metallic tube, for the tobacco.

The tobacco is inserted by removing the piece *E*, or the mouth-piece *D*, and the cigar may be lighted through the orifice *g*, or by removing the piece *E* and then replacing it.

The cigar-pipe is cleaned by removing both the end pieces, *D* and *E*, and wiping it out.

It will be seen that the cigar-pipe cannot get strong, rank, or foul, like the common pipe, on account of the difficulty of cleaning, but that keeping it clean and sweet is a very easy matter.

A pound of tobacco will fill this cigar-pipe over three hundred times.

The choicest smoking-tobacco may be used, and every filling is equivalent to a good cigar, while the objection to the ordinary pipe, in the street or elsewhere, is obviated.

I claim as now, and desire to secure by Letters Patent—

A cigar-pipe, formed of the parts *A*, *B*, *C*, *D*, and *E*, arranged substantially as shown and described, for the purposes set forth.

The above specification of my invention signed by me, this 29th day of April, 1868.

HENRY E. DOSTER.
